UNITED STATES PATENT OFFICE.

ISAAC A. STEIN, OF GALVESTON, TEXAS, ASSIGNOR TO TRIPLE XXX COMPANY, OF GALVESTON, TEXAS, A CORPORATION OF TEXAS.

DESIGN FOR A BOTTLE.

Application filed December 19, 1927. Serial No. 24,544. Term of patent 14 years.

To all whom it may concern:

Be it known that I, ISAAC A. STEIN, a citizen of the United States, residing at the city of Galveston, in the county of Galveston and State of Texas, have invented a new, original, and ornamental Design for a Bottle, of which the following is a specification, reference being had to the accompanying drawing, forming a part hereof.

What I claim and desire to secure by Letters Patent, is the following:

The ornamental design for a bottle, substantially as shown.

In witness whereof, I have signed the foregoing specification.

ISAAC A. STEIN.
